PALMER COX, OF NEW YORK, N. Y.

DESIGN FOR PRINTED FABRIC.

SPECIFICATION forming part of Design No. 24,374, dated June 11, 1895.

Application filed May 9, 1895. Serial No. 548,771. Term of patent 7 years.

To all whom it may concern:

Be it known that I, PALMER COX, a citizen of the United States, residing at New York, county of New York, and State of New York, 5 have invented and produced a new and original Design for Printed Fabrics, of which the following is a specification, reference being had to the accompanying drawing, showing a part thereof, and in which the figure contains a plan of the design.

The leading feature of the design consists in a collocation of groups of "brownies" engaged in various games or pursuits. The groups of "brownies" are arranged in lines 15 ranging transversely of the fabric A. The first group B at the upper left hand corner of the drawing, represents a weird looking brownie strangling a cat with his left hand while his right hand carries a coil of rope. A second 20 figure kneels supplicating for the life of the cat while a third figure holds a lantern. The group C represents a thief "brownie" demanding at the point of a pistol, the money bag carried by another figure, while to the right 25 of this group appears a group D of hoop rollers. The next line below begins with a group E of four "brownies" at a picnic, seated on a cross-tie or beam, eating their luncheon, while a fifth figure is about joining those 30 seated. To the right of this group appears the group F engaged in a game of foot-ball, one figure running with the ball and the others in full chase. The next line of figures begins with group G engaged in a game of base-ball, with an "Uncle Sam brownie" acting as umpire and two other brownies in the act of reading the score card while to the right of this is a group H comprising a policeman chasing a dude whose right leg is in the grasp of a crab. The third group I on 40 this line shows a figure seated on a stump in the act of playing a flute for a couple engaged in a dance; a fourth figure being seated on a stump and gazing intently on the flute player. The last line begins with a goat 45 scene J in which two figures hold the reins of a harnessed goat reared in front of a frightened "Chinese brownie" holding a kite. Then comes the "fisherman group" K, in which the middle brownie holds in his arms a large 50 cat-fish on the fishing-line carried by a second figure, while a third figure appears as if about to insert a finger in the mouth of the fish and lastly there appear two brownies in pursuit of a terrapin, one of the brownies having a 55 drawn bow and being about to shoot the terrapin with the arrow. Here the complete pattern ends and the repeat begins with the next line.

What I claim is—

The design for a printed fabric herein shown and described.

PALMER COX.
